Assistant Examiner — Kelly L Gross

(57) **CLAIM**

The ornamental design for a diagnostic testing apparatus for medical or laboratory purposes, as shown and described.

DESCRIPTION

1.1: Perspective

1.2: Front

1.3: Back

1.4: Left

1.5: Right

1.6: Top

1.7: Bottom

2.1: Perspective

2.2: Front

2.3: Back

2.4: Left

2.5: Right

2.6: Top

2.7: Bottom

Reproductions **1.1** to **1.7** are drawings showing a first embodiment of the diagnostic testing apparatus for medical or laboratory purposes; reproductions **2.1** to **2.7** are drawings showing a second embodiment of the diagnostic testing apparatus for medical or laboratory purposes; the broken lines shown in the figures depict portions of the diagnostic testing apparatus for medical or laboratory purposes that form no part of the claimed designs.
